UNITED STATES PATENT OFFICE.

JAMES H. CROSBY, OF SOMERVILLE, MASSACHUSETTS.

DESIGN FOR A VALVE-CASING.

SPECIFICATION forming part of Design No. 23,938, dated January 1, 1895.

Application filed November 3, 1894. Serial No. 527,841. Term of patent 14 years.

To all whom it may concern:

Be it known that I, JAMES H. CROSBY, of Somerville, in the county of Middlesex and State of Massachusetts, have invented and produced a new and original Design for a Valve-Casing, of which the following is a specification.

Figure 1 is a side elevation of a valve-casing showing my design. Fig. 2 is a top plan view thereof. Fig. 3 is a section thereof.

My design consists in the configuration of the casing shown in the drawings and as hereinafter described, the leading feature of my design being the inclination of the valve cas-

ing with respect to its inlet and outlet or ports.

In the drawings, body A is inclined with reference to its ports a a . Above one of the ports a is a projecting ring-shaped support a' for cover a^2 .

I claim—

The design for a valve-casing substantially as herein shown and described.

JAMES H. CROSBY.
